UNITED STATES PATENT OFFICE.

GOTTWALT SIEBER, OF PLAUEN, GERMANY, ASSIGNOR TO VOGLÄNDISCHE MASCHINEN-FABRIK, OF PLAUEN, GERMANY.

TAMBOUR-FRAME.

1,211,970.

Specification of Letters Patent. Patented Jan. 9, 1917.

Substitute for application Serial No. 843,460, filed June 6, 1914. This application filed December 1, 1915. Serial No. 64,587.

To all whom it may concern:

Be it known that I, GOTTWALT SIEBER, a subject of the German Emperor, residing at Plauen, in Vogtland, in the Kingdom of Saxony, Germany, have invented certain new and useful Improvements in Tambour-Frames, of which the following is a specification.

The present invention relates to tambour frames and has for its object to provide a construction which will render the frame more stable and rigid than the hitherto used structures.

It is well known that with the hitherto used structures the tambour frame is more or less flexible, so that with long machines, as for instance 12 to 14 yd. machines, it has the tendency to become distorted from its rectangular shape. To obviate these drawbacks various improvements have been introduced. Thus, for instance, the longitudinal parts of the frame have been made of reinforced U-shaped or angle iron. But such structures have not entirely avoided the above named defects and have increased the weight of the frame.

My invention will be more fully understood by reference to the accompanying drawing in which similar reference letters denote corresponding parts and in which an elevation of the improved part of the tambour frame is illustrated.

Referring to the drawing *a* denotes one of the longitudinal parts of a tambour frame which according to the present invention is composed of upper and lower girdles 1 and 2 made of thin-walled steel pipes which at their ends are connected by pipe sections 3 and at intermediate points are reinforced by pipe sections 4 and cross wires 5, thus having the form of a beam truss.

In the present embodiment of my invention the reinforcing pipe sections 4 are screwed or otherwise fixed in head pieces 6 mounted on the opposite girdles 1 and 2, and the cross wires 5 are fixed to the said head pieces 6.

What I claim and desire to secure by Letters Patent is:

In a tambour frame, the combination with end parts or members and fabric supporting means borne in the latter, of a longitudinal part, composed of upper and lower tubular steel girdles connected to said members and vertically tubular posts extending between said girdles and diagonal tensioning wires connecting adjacent posts.

In testimony whereof I affix my signature in presence of two witnesses.

GOTTWALT SIEBER.
